US00D989425S

(12) **United States Design Patent** (10) **Patent No.:** **US D989,425 S**
(45) **Date of Patent:** **** Jun. 13, 2023**

(54) **VACUUM CLEANER**

(71) Applicant: **22 Thrasio Twenty Two, Inc.**, Walpole, MA (US)

(72) Inventor: **Ling Liang Ma**, Hangzhou (CN)

(73) Assignee: **22 THRASIO TWENY TWO, INC.**, Walpole, MA (US)

(**) Term: **15 Years**

(21) Appl. No.: **35/513,327**

(22) Filed: **May 24, 2021**

(80) **Hague Agreement Data**

Int. Filing Date: **May 24, 2021**

Int. Reg. No.: **DM/218053**

Int. Reg. Date: **May 24, 2021**

Int. Reg. Pub. Date: **Jan. 7, 2022**

(57) **CLAIM**

The ornamental design for a vacuum cleaner, as shown and described.

DESCRIPTION

Fig. 2.1 is a perspective view of a vacuum cleaner showing the new design;

Fig. 2.2 is a top view thereof;

Fig. 2.3 is a bottom view thereof;

Fig. 2.4 is a right-side view thereof;

Fig. 2.5 is a left-side view thereof;

Fig. 2.6 is a front view thereof; and

Fig. 2.7 is a back view thereof.

(Continued)

Broken lines are used to depict portions of the vacuum cleaner that form no part of the claimed design. Thin lines are used to illustrate portions of the design being behind transparent surfaces.

1 Claim, 7 Drawing Sheets
